Inventor

Harry L. Reed,
By his attorney, Charles S. Foster.

UNITED STATES PATENT OFFICE.

HARRY L. REED, OF DORCHESTER, MASSACHUSETTS, ASSIGNOR TO JOHN E. CROWLEY,
OF DORCHESTER, MASSACHUSETTS.

FUSE.

1,208,004.

Specification of Letters Patent. Patented Dec. 12, 1916.

Application filed December 17, 1915. Serial No. 67,317.

To all whom it may concern:

Be it known that I, HARRY L. REED, a citizen of the United States, residing at Dorchester, in the county of Suffolk and State 5 of Massachusetts, have invented new and useful Improvements in Fuses, of which the following is a specification.

This invention relates to improvements in inclosed or cartridge fuses and particularly 10 to the type of fuse embodying in its construction a telltale circuit of exceptionally fine wire extending from one terminal of the fuse member outwardly through said casing and thence to the other terminal of 15 said fuse. A small amount of explosive substance is arranged about said fine wire adjacent to the point at which it emerges from the casing of the fuse, said explosive substance being covered by a sheet of paper 20 or any other suitable covering which is adapted to be destroyed by the combustion of said explosive substance.

The object of the invention is to provide a suitable handle for a fuse of the type described 25 which may be constructed of insulating material and whereby the fuse may be removed or replaced from the gripping devices which maintain said fuse in electrical contact with an electric circuit without 30 danger of the person removing the same from getting a shock or from being burned, said handle also constituting a barrier which is arranged in front of the telltale of the fuse, thereby preventing the explosive substance 35 from being blown into the face of the person who happens to be standing in front thereof when such an explosion occurs.

The invention consists in the combination 40 and arrangement of parts set forth in the following specification and particularly pointed out in the claims.

Referring to the drawings: Figure 1 is a plan view of a fuse embodying my invention. Fig. 2 is a longitudinal section of the 45 same. Fig. 3 is a section taken on the line 3—3 of Fig. 1.

Like numerals refer to like parts in all views of the drawings.

In the drawings, 4 is a tubular casing, 50 preferably constructed of insulating material such as fiber, having openings 5, 5 at opposite ends. 7 is the fusible element of the fuse, or better known as fuse link. The 55 openings 5, 5 of the casing 4 are closed in

the usual manner by metallic caps 8 which slip over said ends and are secured thereto, preferably by rivets 9 extending entirely through said caps and the adjacent portions of said casing. The caps 8 constitute portions of the fuse terminal and are connected with the fuse 7 by suitable connecting elements 10. To the caps 8 may also be secured blades 11 adapted to be inserted between suitable terminal posts included in 60 the electric circuit which is to be completed by said fuse.

As hereinbefore stated, the casing 4 is constructed of insulating material and to remove the fuse of such a construction from 65 its connection with the terminal posts of the electric circuit it is necessary to grasp said casing and withdraw the same from said terminal post. There is always an element of danger connected with such an operation, 70 for the reason that unless great care is exercised the person grasping said casing is liable to accidentally touch one of the metal caps 8 at the end of said casing with the result that a circuit is completed through said 75 person to the floor of the building or to some other ground, producing a severe shock to said person. To reduce the danger of such an accident, or to eliminate it altogether, a handle 12 has been provided, said handle being 80 constructed of suitable insulating material which is arranged upon the front side of the casing of said fuse and extends from one cap 8 to the other. The ends of said handle are secured preferably by means of the rivets 85 9 to said caps while suitable means are provided to substantially inclose the heads of said rivets in order to insulate the same, said means preferably consisting of extensions 90 13 which, in other words, are continuations 95 of said insulating material bent rearwardly over the heads of said rivets into contact with said handle thus absolutely preventing the person who grasps the handle 12 from touching said rivets. The central portion 100 of said handle is bowed outwardly between the rivets 9 so as to provide ample room to grasp said handle without touching the casing 8. In the type of fuse described, there is what is known as a telltale device connected therewith, which preferably consists of an exceptionally fine conductor 14 which extends from one end of the fuse link at 15 within the casing outwardly through a hole 16 in said casing near the center and in the 110

front face thereof, thence along the outer surface of said casing to the cap 8 which is connected with the opposite end of the fuse link surrounding the conductor.

- 5 At the point where the conductor 14 emerges from the casing a label or covering of suitable material is placed over said conductor beneath which is arranged an explosive or combustible substance arranged in
- 10 direct contact with said conductor. When the fusible element 7 is melted or blown, a short circuit or overload current which previously passed through said fuse is diverted through the fine conductor 14 and causes
- 15 said conductor to fuse or be blown, thereby igniting the explosive substance beneath the sheet material. The position of said telltale is usually at the front of the casing 8 and in plain view of persons approaching the
- 20 same so as to permit the condition of said fuse to be instantly discerned. It will be evident that with such an arrangement of the telltale that considerable danger will always be present to the person inspecting or
- 25 approaching the casing containing the fuse, from the exploding of said explosive substance which might happen at any time without any warning, and thus blow directly into the face of said person.
- 30 It is one of the objects of this invention to so place said handle that it will serve as a barrier between said explosive substance and the person inspecting said fuse so as to prevent particles of said explosive substance
- 35 from being thrown into the face of said person.

Having thus described my invention what

I claim and desire by Letters Patent to secure is:

1. A fuse having, in combination, a tubular casing, closures for opposite ends of said casing, a handle constructed of insulating material, metallic means for securing opposite ends of said handle to said closures, and means constituting portions of said handle adapted to inclose said metal securing means to insulate said means. 40

2. A fuse having, in combination, a tubular casing, a cap constructed and arranged to close each end of said casing, rivets extending through said caps and into said casing, a handle constructed of insulating material adapted to be secured by said rivets to said caps, and means on said handle adapted to cover the ends of said rivets and insulate 55 the same. 50

3. A fuse having, in combination, a tubular casing, a cap constructed and arranged to close each end of said casing, rivets extending through said caps and into said casing, a handle constructed of insulating sheet material adapted to be secured by said rivets to said caps, and extensions on said handle bent backwardly toward said handle and adapted to cover the ends of said rivets to 60 insulate the same. 65

In testimony whereof I have hereunto set my hand in presence of two subscribing witnesses.

HARRY L. REED.

Witnesses:
